UNITED STATES PATENT OFFICE.

ANDREW R. SMITH, OF CRAFTON, PENNSYLVANIA.

ATTACHMENT FOR SAWS.

Application filed September 13, 1924. Serial No. 737,464.

To all whom it may concern:

Be it known that I, ANDREW R. SMITH, a citizen of the United States, residing at Crafton, in the county of Allegheny and State of Pennsylvania, have invented new and useful Improvements in Attachments for Saws, of which the following is a specification.

My invention relates to attachments for saws.

The object of this invention is to provide for hack-saws, or saws having a U-shaped frame which supports the saw-blades at its open side, attachments whereby the distance between the saw-blade and the back of the frame may be adjusted to one or more predetermined limits without any necessary modification or adjustment of the frame itself. Other minor objects appear herein-after.

Referring to the accompanying drawing, Fig. 1 is a side view of a hack-saw with my invention attached thereto; Fig. 2, an end view of the left-hand portion of Fig. 1, looking to the right; Fig. 3, a perspective view of one of my attachments; Fig. 4, a detail view showing two of my attachments arranged in combination to provide an extraordinary distance between the saw blade and the back of the saw-frame; Fig. 5, a fragment of one of my attachments showing a modification; and Fig. 6, a side view of a screw-lug to fit one of the two right hand holes in Fig. 5. Fig. 7 is a section on the line VII—VII on Fig. 5, showing a screw stud applied to one of the holes 20. Fig. 8 is a view showing in perspective a portion of one of my attachments with another modification.

On the drawing, I show a hack-saw having a U-shaped frame comprising the back member 1 and the end members 2 and 3. The back-member may be adjustable but the end members need not be adjustable. I have shown the frame composed of a single piece of metal having the rectangular loops 4 and 5 riveted to the ends of the end members 2 and 3.

6 is the handle having the metal stud 7 projecting through the loop 4 and provided with the lateral pin 8. 9 is a metal rod in the loop 5 and projecting at both ends beyond the loop, the inner end has the lateral pin 10 and the outer end is threaded and has the winged nut 11 working thereon against the outer end of the loop 5. The saw blade

12 has at its ends eyes through which the said pins 8 and 10 project. By turning the nut in one direction the saw-blade is rigidly held in place on the pins in a manner readily understood. The nut is turned in the opposite direction to release the saw-blade. The mechanism so far described is old and is presented merely to show one of the many forms of hack-saws to which my invention is applicable.

My invention comprises the attachments or extension pieces 13 adapted at one end for ready connection to the end members 2 and 3, and at the other end for the reception of the handle 6 and its stud 7 and the rod 9 and its nut 11. The attachments are preferably made exactly alike, each comprising metal bar or strip 14 having at one end the loop 45 precisely like the loops 4 and 5, and at the other end means, as the studs 15 and 16, for attaching it to the frame-end 2 or 3. The strip 14 is preferably of the same width as the ends 2 and 3 and is applied to the end 2 or 3 so as to lie thereon with their sides in contact and with the stud 15 at the inner edge of the member and the stud 16 at the outer edge thereof, the former being nearer the back member 1 than the latter. The studs are arranged in a line which makes an angle with the direction of the length of the attachment 13, the stud 15 being the farther out on the attachment. The studs have the necks 17 which have a length equal to the thickness of the end members 2 and 3 and lie against the latter, and have at their outer ends the heads 18 which lie over the end members to prevent the separation of the attachments from the end members by any lateral movement of the attachments. The studs are so arranged that, when the necks 17 are engaged with opposite edges of an end member, the attachment will be parallel with the end member. The length of the attachment is such that its looped end will extend beyond the loop on the adjacent end member the desired distance. The intermediate portion of each attachment has the curve or bend 19 to receive the loop 4 or 5.

In Fig. 1, the full lines show the saw-frame equipped with my invention and ready for use, the dotted lines for the parts 6 to 11 showing the latter where they would appear normally with the saw-frame un-equipped with my invention.

To apply my invention, the parts 6 to 11

are removed from the frame. Two attachments 13^a are applied to the end members 2 and 3, one on one side of the member 2 and the other on the opposite side of the member 3. Each attachment is first held diagonally of the end member to which it is to be applied, with the studs 15 and 16 standing at about right angles to the end member. The heads 18 being spaced apart at least equal to the width of the end member, the attachment is moved bodily toward the end member until the attachment lies on the end member. Each attachment is then swung inwardly into registry with the adjacent end member. The parts 6 to 11 are applied to the looped end of the attachment precisely as they were originally applied to the looped ends of the frame.

It is seen that by my invention the distance between the saw-back and the saw blade may be increased a predetermined amount beyond its normal position without necessitating any modification or adjustment of any part of the saw to which my improvement is applied. It is only necessary to remove the saw blade from its normal position; apply two of my attachments to the end members of the frame; and then attach the saw blade to suitable attaching means carried by the free ends of the attachments. These means may be those carried by the loops 4 and 5 or the saw blade may be supported by other suitable devices.

35 I may make my attachments applicable to frame-ends of different widths by providing a plurality of openings 20 in the stud-carrying end thereof, so that a screw-stud 15^a, shown in Fig. 6, may be screwed into the proper one of the holes 20.

In Fig. 8 I have shown my attachment, marked 13^a provided with the turned-over flanges or ears 15^b and 16^b, the latter functioning the same as the studs 15 and 16.

45 I claim—

1. In a saw, a U-shaped frame; means on the end members thereof for supporting saw holding devices; extension members readily attachable to said end mem-

bers and projecting outwardly beyond the said means, and means at the outer ends of said extension members for supporting saw-blade holding devices.

2. In a saw holding attachment for a saw having a U-shaped frame and means on the end members of the frame for supporting saw-holding devices, extension members readily attachable to the said end members and projecting outwardly beyond the said supporting means, and means at the outer ends of the extension members for supporting saw-blade holding devices.

3. In an extension member for the end members of a hack-saw frame, a strip of metal, lateral projections at one end thereof arranged to engage opposite edges of one of said members and preventing the extension member from moving inwardly beyond a predetermined position, and means on the outer end of the said strip for supporting a saw-holding means.

4. In an extension member for an end member of a hack-saw frame having means on one end member for supporting a saw-holding device, a strip of metal, lateral projections at one end thereof arranged to engage opposite edges of one of said end members and preventing the said strip of metal from moving inwardly beyond a predetermined position; and means on the outer end of the said strip for supporting the said saw-holding device.

5. In an extension member for the end members of a hack-saw frame, a strip of metal, lateral projections at one end thereof arranged to engage opposite edges of one of said end members and preventing the extension member from moving inwardly beyond a predetermined position, means on the outer end of the said strip for supporting a saw-holding means, and means for interlocking the projections with the end member to which it is applied.

In testimony whereof I hereunto affix my signature this 12th day of September, 1924.

ANDREW R. SMITH.
